UNITED STATES PATENT OFFICE

RUSSELL G. KING AND HARRY C. KING, OF WASHINGTON, DISTRICT OF COLUMBIA

LADDER SCAFFOLD

Application filed August 7, 1926. Serial No. 127,758.

This invention relates to improvements in a portable scaffold which may be employed for work upon either the exterior or interior of a building, and has for one of its objects 5 to provide a scaffold of this character which is constructed of built up ladder sections from the ground or floor to the top of the building or at any desired height, and which is provided with scaffold platform boards securely attached to the ladder sections at 10 any desired point.

Another object of this invention is the provision of an adjustable means for readily attaching the scaffold boards and the ladder 15 sections to the window or door frames of a building for positioning the scaffold at any desired distance from the building.

A further object of this invention is to provide a ladder scaffold of this nature having means for securing the end portions of the platform boards to certain of the rungs of the ladder sections, either singly or in end lapped relation to each other, and the further provision of means for bracing the 20 platform boards from points remote from their attachment to the rungs and to the stiles or standards of the ladder sections.

A further object of this invention is the provision of a ladder scaffold consisting of 25 a few parts and capable of being readily set up or dismantled by workman or laborers.

And a still further object of this invention is to provide a ladder scaffold of this nature consisting of few parts, cheap to 30 manufacture, and which can be sold upon the market at a nominal cost, and whilst we will herein illustrate, describe and claim the preferred embodiment of our invention, we hereby reserve the right to make such variations and alteration in the general structure 35 thereof from time to time as we may deem expedient and which will neither depart from the spirit of the invention or the scope of the claims.

40 In the drawings:

Figure 1 is a front view, partly broken away, showing the application of the invention to a building.

Fig. 2 is a top plan view of Figure 1, 45 partly broken away and partly in section,

showing the means employed for attaching the scaffold sections to the window frames of a building.

Fig. 3 is a top plan view showing the specific means employed for securing the 55 platform boards of the ladder sections to the window or door frames of a building.

Fig. 4 is a fragmentary detail view of the locking means employed upon the window attaching means for the scaffold. 60

Fig. 5 is a detail sectional view, on the line 5—5 of Figure 4 showing the specific construction of the locking tongue of the pawl lever employed, showing its specific co-action with the ratchet bar of the invention. 65

Fig. 6 is a fragmentary perspective view of one of the swinging retaining arms carried by the window attaching means for engaging the platform boards for securing and positioning the ladder sections relative to a 70 wall of a building.

Fig. 7 is a detail view on line 7—7 of Figure 2, looking in the direction of the arrows, showing the means for bracing the platform boards to the ladder stiles and securing the 75 same to the frame of a door or window.

Fig. 8 is a fragmentary detail edge view, partly broken away and partly in section, showing the specific means employed for securing the platform boards to the rungs of 80 the ladder sections and the diagonal bracing frame for securing the platform boards to the stiles of the ladder sections.

Fig. 9 is a fragmentary detail view, partly 85 in section, showing the specific means employed for securing the platform bracing frame to the stiles of the ladder sections, and

Fig. 10 is an inverted perspective view of the plate or cleat employed for securing the contiguous ends of the platform boards 90 to the rungs of the ladder sections.

Referring to the drawings, wherein similar reference characters denote like parts throughout the several views of the drawings, A represents the wall of a building 95 and B the window frame. Positioned adjacent the wall A of the building are the ladder sections 1. These ladder sections 1 comprise a plurality of superimposed sections extending from the ground or floor to 100

any desired height or to the top of a building if necessary and are positioned along a vertical line approximately between the vertical rows of windows. Each of the ladder sections 1 is of a convenient length to permit the ready handling of the same in building up the ladder scaffold and each section is similarly formed by being slightly convergent in its longitudinal direction so that the wide end of each succeeding superimposed section will embrace the narrow end of the section preceding it. The ladder sections comprise any desired number of rungs 2 and have each of the ends of their stiles provided with the transverse notches 3 and in proximity to one of the ends, for instance the upper end, with the elongated rung 4 positioned outwardly of the stiles and provided with the threaded ends 5 upon which are threaded the wing nuts 6. To build up the ladder sections the notches 3 in the broad ends are positioned so as to embrace the narrow ends and engage the projecting ends of the rungs 4 and retained in such position by the wing nuts 6 upon their threaded ends 5, while the lower most rung 2 of the next succeeding section is seated in the notches 3 in the adjacent ends of the next preceding section, whereby the ladder sections are built up successively to any desired height.

At any desired point along the ladder sections, but preferably opposite a window frame B, there is positioned a platform board 7 of a length adapted to rest upon two opposing rungs 2 of the ladder sections and on a plane opposite the window frame B, but preferably adjacent the bottom portion thereof. The platform boards 7 are each formed with two rows of longitudinally aligned holes 8 adjacent the edges thereof and preferably positioned transversely opposite each other as clearly shown in Figure 2 and which holes 8 may be any desired distance apart.

For maintaining the platform boards and consequently the ladder sections to which they are attached, as will be hereinafter described, there is provided opposite each window frame, a scaffold board 7 and for maintaining the scaffold boards 7 and the ladder sections 1 at any desired spaced relation from the wall of the building there is provided a clamping bar for each window frame B. The clamping bar consists of a supporting bar 9 having at one end the loop 10 through which is slidably mounted the ratchet bar 11 formed on its outer face with the ratchet teeth 12 and also having the loop 13 for slidably engaging the supporting bar 9. The outer ends of the supporting bar 9 and the ratchet bar 11 are provided with the screw threads 14 upon which are threaded the internally threaded sleeves 15 which are formed square in cross section as shown at 16 in

Figure 3. The ends of the sleeves 15 are provided with the solid rounded heads 17. Pivotal secured to the supporting bar 9 by the bolt 18 are the bifurcated members 19 of the pawl locking lever 20 provided with the locking tooth 21, as clearly shown in Fig. 5 and adapted to ride over the teeth 12 on the ratchet face of the ratchet bar 11 when the supporting bar 9 and the ratchet bar 11 are moved in outward opposite directions relative to each other, the telescopic relation that one bears to the other permitting this movement so that when attaching this clamping member to a window frame, the bars 9 and 11 are extended outwardly until their respective heads engage the opposite sides of the window frame and at this juncture the respective sleeves 15 are readily screwed outwardly by the hand of a workman or if necessary a wrench, the square portions of the sleeves permitting the same to be readily and firmly grasped by the hand for screwing the same outwardly so that when the heads 17 impinge the window frame the supporting bar 9 and the ratchet bar 11 will be forced backwardly towards each other in a manner that the tooth 21 of the pawl lever 20 will engage a tooth 12 of the ratchet bar in such a manner that the locking lever 20 will be forced inwardly and held against the ratchet face of the bar 11 and be securely locked against movement until it becomes necessary to release this lever from locking engagement by a workman who must exert force by an outward pull on the locking lever 20 when it is desirable to release this clamping member, this action being due to the angular formation of the locking pawl as the tooth 21 is offset from a line drawn from its pivotal point 18 to the end of the lever 20, as clearly illustrated in Figures 4 and 5.

Also pivotally mounted upon the supporting bar 9, as by the bolt 22, are the bifurcated ends 23 of the scaffold board retaining rods 24, each having the screw threaded end 25 adapted to have adjustably mounted thereon the internally screw threaded head 26 of the depending pin 27, which is designed to extend at right angles to the rod 24, whereby after the clamping member has been secured to the window frame the retaining rods 24 may be swung laterally to any desired degree in either direction upon the supporting bar 9 of the clamping member so that by adjusting the heads 26 on the screw threaded ends 25, the pins 27 may be positioned for bringing the pins into registration with any of the holes 8, adjacent either of the side edges of the platform boards 7 at any longitudinal point between the ladder sections to thereby maintain the platform boards 7 and the ladder sections at any desired distance from the wall of the building without the exercise of any special degree of accuracy

in the vertical alining of the platform boards and ladder sections when erecting and attaching the same to the wall of a building.

For firmly securing the platform boards 7 to the ladder sections 1, there is provided a clamping plate 28 provided with a centrally bent U-shaped portion 29 and the holes or openings 30 at either side of the U-shaped portion 29 adjacent each end thereof. The holes 30 are spaced apart a distance equal to the distance between the holes 8 in the longitudinal direction of the platform boards 7, so that when the board 7 is placed to rest upon a rung 2 of the ladder sections 1, the clamping member 28 is so positioned that the U-shaped portion 29 is placed beneath the rung 2 and the flat portions extending therefrom will bear against the bottom of the platform boards 7, with the holes 30 in registration with a hole 8 of the platform board 7 at either side of the rung 2 of the ladder sections, the board 7 being firmly held upon the rung 2 by the bolts 31, which pass through the respective holes 8 of the platform boards and the holes 30 of the clamping member and are retained thereon by the wing nuts 32. The bolts 31, may be of sufficient length to pass through the overlapping ends of the platform boards 7, as clearly shown in Figure 8, to thereby rigidly secure the platform boards 7 of the contiguous tiers of the ladder scaffold sections firmly together upon the respective rungs.

To further secure the platform boards 7, there is provided a bracing frame comprising the spaced side members 33 secured together by the two cross struts 34, shown in Fig. 7, arranged in a manner to give the bracing frame a slightly convergent formation. The upper ends of the side members 33 have secured thereon by the bolts or rivets 35, the hook members 36, adapted to engage the eyes 37, of the eye-bolts 38, which are adapted to project through a pair of transversely alined holes 8 of the platform boards 7 and secured to the latter by the wing nuts 39. At the lower ends of the side members 33 of the bracing frame and pivotally mounted thereon by the bolts or rivets 40 are the two spaced clamping plates 41, each of the plates 41 being slightly bent at 42 and 43 to provide the inturned ends 44, the plates 41 are adapted to be swung into position at either side of the stile of the ladder sections 1 and retained in firm gripped relation thereon by the bolts 45, between their pivotal point 40 and the ladder stile 1 and retained in firm engagement with the ladder stile by the wing nuts 46.

From the foregoing described invention, it is clear that we have provided a ladder scaffold having many meritorious advantages, in that, the ladder sections 1 are of a convenient length and contain any desired num-

ber of rungs 2. These ladder sections are formed to readily build up the same in superimposed relation from the ground or floor to any desired height between the vertical rows of doors or windows of a building, the ladder sections being built up in tiers as the scaffold progresses. After a certain number of the ladder sections are built up to a sufficient height a platform board 7 is positioned upon certain of the rungs 2 of the ladder sections opposite a window and clamped to the respective rungs by the clamping cleats 28 and the bolts 31, as hereinafter described. The scaffold boards 7 are of any suitable length and are formed with longitudinal rows of equi-spaced holes 8 so as to accommodate the scaffold to either narrower or wider window frames in which instance after the scaffold sections are positioned by the narrow windows the clamping plates 28 which are secured by the bolts 31 to the rungs 2, may be moved or adjusted to other holes 8 of the scaffold boards so as to position the ladder sections at a lesser or greater distance apart and the eye-bolts 38 are likewise adjusted in the holes 8, so that the bracing frames may be swung in a downwardly inclined direction so as to embrace and clamp the stiles 1 of the ladder sections at any convenient point below the rungs 2 to which the scaffold boards have been previously secured and firmly clamped to the ladder stiles by the bolts 45 and their wing nuts 46. These wing nuts 46 are preferably positioned at the inner sides of the bracing frame so as to be conveniently operated by a single workman.

After this has been accomplished the scaffold boards are secured to the window frames by the extension member shown in Figures 1, 2 and 7, and more specifically shown in Figures 3, 4, 5 and 6. The extension members each comprise a supporting bar 9 and a ratchet bar 12 arranged to have sliding engagement relative to each other for positioning the same between the opposing faces of window or door frames of any widths and thereafter by screwing the heads 17 outwardly until the same firmly impinge the window frame, the retroactive tendency of the bars 9 and 12 will cause the tooth 21 of the locking pawl lever 20 to engage a tooth 12 of the ratchet bar 11 in such a manner that the lever 20 will be swung to lie flush against the ratchet bar 11 and firmly lock the extension members against movement. The laterally swinging arms 24, which are pivotally mounted upon the supporting bar 9 will then be swung in either direction between the respective ladder sections in a manner that the heads 26 of the engaging pins 27 may be so accurately adjusted upon the arms 24 so that the pins 27 will engage any desired holes 8 of the scaffold boards 7 at either of the side edges thereof, whereby the scaffold may be speedily erected without

any special regard to the true vertical alignment thereof as the necessary adjustments can be subsequently made for rigidly maintaining the scaffold in spaced relation to the wall 5 of a building. The specific manner of mounting the scaffold boards upon the ladder sections for maintaining the same against lateral displacement relative to each other and the specific means for maintaining the scaffold 10 against inward or outward movement relative to the building in a speedy and expeditious manner are meritorious results attained by our invention.

We claim:

1. In a scaffold of the class described, the 15 combination with parallel vertical rows of superimposed ladder sections, means for securing the ladder sections together, of scaffold boards provided with longitudinal rows 20 of holes in proximity to the edges thereof, means to rigidly secure the scaffold boards to said ladder sections for maintaining the sections in vertical parallel spaced relation to each other, slidable extension means for readily 25 positioning the same between the inner opposing faces of window frames, locking means carried by said extension means, and adjusting means carried by the ends of said extension means for impinging the opposing inner faces of a window frame for causing 30 the locking means to be firmly locked by the retractile movements of the extension means.

2. In a scaffold of the class described, the 35 combination with parallel vertical rows of superimposed ladder sections, means for securing the ladder sections together, of scaffold boards provided with longitudinal rows of holes in proximity to the edges thereof, 40 means to rigidly secure the scaffold boards to said ladder sections for maintaining the sections in vertical parallel spaced relation to each other, slidable extension means for readily positioning the same between the inner 45 opposing faces of window frames, locking means carried by said extension means, and rotatable adjusting means having square internally threaded sleeve shanks carried by the ends of said extension means for impinging 50 the opposing inner faces of a window frame for causing the locking means to be firmly locked by the retractile movements of the extension means.

3. In a scaffold of the class described, the 55 combination with parallel vertical rows of superimposed ladder sections, means for securing the ladder sections together, of scaffold boards provided with longitudinal rows of holes in proximity to the edges thereof, 60 means to rigidly secure the scaffold boards to said ladder sections for maintaining the sections in vertical parallel spaced relation to each other, slidable extension means for readily positioning the same between the 65 inner opposing faces of window frames, lock-

ing means carried by said extension means, adjusting means carried by the ends of said extension means for impinging the opposing inner faces of window frames for causing the locking means to be firmly locked by the retractile movements of the extension means, laterally swinging arms pivotally connected to said extension means, and means adjustably mounted upon the free ends of said laterally swinging arms for engaging certain of the holes of said platform boards to maintain said platform boards and ladder sections in vertical spaced relation to the wall of a building.

4. In a scaffold of the class described, the 70 combination with parallel vertical rows of superimposed ladder sections, means for securing the ladder sections together, of scaffold boards provided with longitudinal rows of holes in proximity to the edges thereof, 75 means to rigidly secure the scaffold boards to said ladder sections for maintaining the sections in vertical parallel spaced relation to each other, slidable extension means for readily positioning the same between the inner 80 opposing faces of window frames, locking means carried by said extension means, rotatable adjusting means carried by the ends of said extension means for impinging the opposing inner faces of window frames for causing the locking means to be firmly locked by the retractile movements of the extension means, laterally swinging arms pivotally connected to said extension means, and pin carrying members adjustably mounted upon the free ends of said laterally swinging arms for 85 engaging certain of the holes of said platform boards to maintain said platform boards and ladder sections in vertical spaced relation to the wall of a building.

5. In a ladder scaffold of the class described, the combination with parallel vertical rows of superimposed ladder sections, means for securing the ladder sections together, of scaffold boards rigidly secured to a rung of certain of the ladder sections for 90 maintaining the sections in vertical parallel spaced relation to each other, said scaffold boards having longitudinal rows of holes through and adjacent to the edges thereof, 95 extension means for positioning the same between the opposing inner faces of window frames, said extension means comprising a supporting bar, a ratchet bar, means to provide for the sliding engagement of said supporting bar and said ratchet bar, a locking pawl lever pivotally mounted upon said supporting bar and adapted to embrace said ratchet bar, means carried by said locking pawl lever to engage the ratchet teeth of said ratchet bar, and rotatable members threaded upon the outer ends of said supporting bar 100 and said ratchet bar for firmly impinging the opposing inner faces of window frames, whereby when said rotatable members of said 105

extension member are adjusted for impinging the faces of a window frame the retroactive tendency of the supporting bar relative to the ratchet bar will cause said locking 5 pawl lever to become firmly locked upon said ratchet bar.

6. In a ladder scaffold of the class described, the combination with parallel vertical rows of superimposed ladder sections, 10 means for securing the ladder sections together, of scaffold boards rigidly secured to a rung of certain of the ladder sections for maintaining the sections in vertical parallel spaced relation to each other, said scaffold boards having longitudinal rows of holes through and adjacent to the edges thereof, 15 extension means for positioning the same between the opposing inner faces of window frames, said extension means comprising a supporting bar, a ratchet bar, loops to provide for the sliding engagement of said supporting bar and said ratchet bar, a locking pawl lever pivotally mounted upon said supporting bar and adapted to embrace said 20 ratchet bar, a tooth carried by said locking pawl lever adapted to engage the ratchet teeth of said ratchet bar, and rotatable members threaded upon the outer ends of said supporting bar and said ratchet bar for firmly impinging the opposing inner faces of window 25 frames, whereby when said rotatable members of said extension members are adjusted for impinging the faces of a window frame the retroactive tendency of the supporting 30 bar relative to the ratchet bar will cause the tooth of said locking pawl lever to become firmly locked upon said ratchet bar.

7. In a ladder scaffold of the class described, the combination with parallel vertical rows of superimposed ladder sections, 40 means for securing the ladder sections together, of scaffold boards rigidly secured to a rung of certain of the ladder sections for maintaining these sections in vertical parallel spaced relation to each other, said scaffold boards having longitudinal rows of holes through and adjacent the edges thereof, 45 extension means adapted to be secured between the opposing inner faces of window frames, 50 said extension means comprising a supporting bar, a ratchet bar, means to provide for sliding engagement between said supporting bar and said ratchet bar, a locking pawl lever pivotally mounted upon said supporting bar 55 and adapted to embrace said ratchet bar, means carried by said locking pawl lever to engage the ratchet teeth of said ratchet bar, rotatable members threaded upon the outer ends of said supporting bar and said ratchet 60 bar for firmly impinging the opposing inner faces of window frames, whereby when said rotatable members of said extension member are adjusted for impinging the faces of a window frame the retractile tendency of the 65 supporting bar relative to the ratchet bar will

cause said locking pawl lever to become firmly locked upon said ratchet bar, laterally swinging arms pivotally mounted upon said supporting bar and embracing said ratchet bar, said laterally swinging arms having their free ends screw threaded for a distance, and means adjustably threaded upon the screw threaded ends of said arms for adjustably engaging certain of the holes of said scaffold boards intermediate of said ladder sections, 70 whereby to maintain said scaffold boards and said ladder sections in vertical spaced relation to the wall of a building.

8. In a ladder scaffold of the class described, the combination with parallel vertical rows of superimposed ladder sections, 75 means for securing the ladder sections together, of scaffold boards rigidly secured to a rung of certain of the ladder sections for maintaining these sections in vertical parallel spaced relation to each other, said scaffold boards having longitudinal rows of holes through and adjacent the edges thereof, extension means adapted to be secured between the opposing inner faces of window frames, 80 said extension means comprising a supporting bar, a ratchet bar, loops to provide sliding engagement between said supporting bar and said ratchet bar, a locking pawl pivotally mounted upon said supporting bar and 85 having arms adapted to embrace said ratchet bar, means carried by said locking pawl lever adapted to engage the ratchet teeth of said ratchet bar, rotatable sleeve members threaded upon the outer ends of said supporting bar and said ratchet bar for firmly impinging the opposing inner faces of window 90 frames, whereby when said rotatable members of said extension member are adjusted for impinging the faces of a window frame 95 the retroactive tendency of the supporting bar relative to the ratchet bar will cause said locking pawl lever to become firmly locked upon said ratchet bar, laterally swinging arms pivotally mounted upon said supporting bar and embracing said ratchet bar, said laterally swinging arms having their free ends screw threaded for a distance, and pin carrying blocks adjustably threaded upon the screw threaded ends of said arms for adjustably engaging certain of the holes of said scaffold boards intermediate of said ladder sections, whereby to maintain said scaffold boards and said ladder sections in vertical 100 spaced relation to the wall of a building.

9. In a scaffold of the class described, the combination with vertical rows of superimposed ladder sections, of scaffold boards secured to said ladder sections and having longitudinal rows of holes, securing plates positioned at the underside of said boards and embracing certain of the rungs of said ladder sections, and means adapted to pass through said securing plates and certain of 105 110 115 120 125 130

the holes of said scaffold boards for rigidly securing the scaffold boards to the ladder sections.

In testimony whereof we affix our signatures.

RUSSELL G. KING.
HARRY C. KING.
